STEP MOVEMENT MECHANISM FOR TYPE-WRITERS AND THE LIKE

William C. Roe, Elyria, Ohio, assignor, by mesne assignments, to Printel Communication Systems, Inc., New York, N. Y., a corporation of New York

Original application February 5, 1932, Serial No. 591,224, now Patent No. 1,991,416, dated February 19, 1935. Divided and this application January 31, 1935, Serial No. 4,339

13 Claims. (Cl. 178—40)

This invention relates to receivers of electrically transmitted intelligence, of the class wherein an element, such for example as a printing type cylinder, is moved to various character printing positions, upon the reception of transmitted selective current impulses; this class of apparatus being sometimes referred to as telegraphic typewriters.

The invention relates more particularly to electrically controlled mechanisms of the step movement class for effecting a step by step positioning movement of the type cylinder or other corresponding element of the receiver.

This application is divisional from my application Serial No. 591,224 filed February 5, 1932, patented Feb. 19, 1935, No. 1,991,416, for improvements in Receivers for the electrical transmission of intelligence. In that application is illustrated and described a complete receiver of the class above referred to and an electrical system for controlling the same and reference may be had thereto for a complete description of parts of the system and apparatus herein more briefly described or referred to.

It is an object of the present invention to provide an improved apparatus of the kind referred to in which transmitted electrical impulses may actuate a letter printing type selective apparatus whereby, in an improved manner, to translate the impulses into letters and words.

Another object is to provide in a receiver of the class comprising a type cylinder or the like having a plurality of characters thereon and adapted to be selectively moved to position it selectively with respect to the characters thereon, an improved positioning mechanism therefor responsive to a variety of predetermined electrical impulses transmitted thereto.

Another object is to provide in a receiver of the class referred to, having a type cylinder or the like movable rotatively and axially to position it selectively with respect to the characters thereon, an improved positioning mechanism therefor.

Another object is to provide an improved step-movement mechanism.

Another object is to provide an improved step-movement mechanism responsive to electrical impulses.

Another object is to provide a step-movement mechanism for selectively positioning the type cylinder or the like of a telegraph typewriter or the like in response to the reception of electrical impulses or groups of impulses and in which, to position the type cylinder, it may be moved ro-

tatively or axially and in these directions separately or concurrently.

Other objects will be apparent to those skilled in the art to which my invention appertains.

My invention is fully disclosed in the following 5 description taken in connection with the accompanying drawings, in which:

Fig. 1 is a view in some respects diagrammatic illustrating a part of an embodiment of my invention, whereby a type cylinder which I may employ 10 may be selectively moved to printing position and returned to a normal position;

Fig. 2 is a fragmentary view taken from the plane 2 of Fig. 1;

Fig. 3 is a view taken from plane 3 of Fig. 2; 15

Fig. 4 is a view to an enlarged scale of a ratchet element which I may employ and illustrated in Fig. 1;

Fig. 5 is an elevational view with parts broken away for clearness, of an apparatus in which my invention may be embodied, and illustrating also in actual structural form, certain parts which are illustrated diagrammatically in Fig. 1;

Fig. 6 is a fragmentary view taken from the plane 6 of Fig. 5;

Fig. 7 is a top plan view of an actual embodiment of my invention, with parts broken away to simplify the drawings;

Fig. 8 is a fragmentary view taken from plane 8 of Fig. 7 and with parts omitted for simplicity; 30

Fig. 9 is a fragmentary view taken from plane 9 of Fig. 5, with the parts drawn to a smaller scale, approximately half of the scale of Fig. 5;

Fig. 10 is a fragmentary view taken from plane 10 of Fig. 5.

In general, the apparatus in which my invention is embodied comprises a type cylinder 1, mounted for rotary movement on its axis and also for movement longitudinally of its rotary axis. The cylinder has a cylindrical surface thereof divided up into preferably 42 divisions in each of which may be provided a type character, number or letter. By rotating the cylinder and/or moving it longitudinally, any one of the characters may be brought into position to be printed upon a strip of paper as will be more fully described or referred to hereinafter.

The mechanism to be fully described herein after for rotating and reciprocating the cylinder 1, is actuated by electrical impulses transmitted to the apparatus from the remote or sending station. Preferably, the impulses are transmitted over two circuits, the impulses on one circuit functioning to rotate the type cylinder 1, and those of the other functioning to move

25

it longitudinally; and in either case, the apparatus responds to each single impulse to rotate the cylinder a single space or division or to move it longitudinally a single space or division.

5 In Fig. 1 I have illustrated in semi-diagrammatic form an apparatus embodying the general principles of my invention, and in the other figures have illustrated the same mechanism but more as it actually appears in a preferred form 10 when produced for practical or commercial purposes.

Referring to Fig. 1, I have reproduced at 7 and 8 two impulse receiving magnets, each having associated therewith an armature 35 and 36 pivotally supported at 37—37 one end of each being adapted to be attracted by the magnet and the other end of each having a finger 38—38 engaging an arm 39—39 of a pair of bell cranks 40—40, pivoted at 41—41. The other arms 42—42 15 of the similar bell cranks 40—40, are bifurcated at their free ends to provide fingers 43—44, provided each at the free ends thereof with downwardly projecting pawls 45 and 46. These pawls straddle elongated longitudinally movable ratchet pieces 47—47 provided on their lateral edges with longitudinally extending rows of teeth 65 and 66 respectively, engageable by the pawls 45 and 46.

Extending downwardly from the ratchet pieces 30 47—47 are pins 67—67 engaged upon their rearward sides by the upper free ends of springs 68—68, see Figs. 5 and 10. The springs 68 are preferably formed from flat steel strips supported and disposed to exert a forward resilient thrust 35 on the pins 67, thrust portions 69—69 being provided on the upper free ends of the springs 68 and interposed between the springs and the pins 67, whereby, in all relative operative positions of the pins 67 and springs 68, the thrust of the 40 spring may be transmitted from the upper extreme end of the spring.

The lower ends of the springs 68 are rigidly connected as by screws 70 to a head 71 rotatably supported in ball bearings 72, but adapted, in a 45 manner to be described, to take up a normal position such as that illustrated in Fig. 5, in which the springs 68 are bent to continuously exert a forward thrust on the pins 67 and the ratchet pieces 47.

40 In connection with the apparatus thus far described, when a magnet such as the magnet 7 is energized with one or more impulses, the armature 35 thereof will be rocked clockwise and correspondingly rock the bell crank 40 counter-clockwise against the clockwise torque of a spring 75. The spring 75 normally maintains the pawl 45 against the teeth 65, and the pawl 46 out of engagement with the teeth 66, and the ratchet pieces 47 are continuously resiliently 55 pressed forward by the springs 68 as above described. Therefore, upon energization of the magnet 7, say, by one impulse, the pawl 46 will be moved into engagement with a tooth 66 to transfer the ratchet piece holding function from 60 the pawl 45 to pawl 46.

When the magnet 7 is de-energized at the end of the said impulse, the spring 75 returns the pawl 45 toward the teeth 65, but the rearwardly inclined edge, such as the edge 76 of the tooth 70 66, permits a slight forward movement of the ratchet piece 47 during the inward movement of the pawl 45 and outward movement of the pawl 46 so that during the return of the pawl 45 toward a small distance by the spring 68 so that the pawl 45, as it returns, engages the next suc-

ceeding tooth 65 and the ratchet piece 47 will thus be advanced a distance corresponding to one tooth space. Thus also, upon energizing the magnet 7 with a succession of impulses, the bell crank 40 will be vibrated back and forth, in one direction by the magnet 7 and in the other by the spring 75, and the ratchet piece 47 will be stepped forwardly rapidly a corresponding number of teeth or steps.

5 In the forward ends of the ratchet pieces 47 10 are provided upstanding pins 48 over which are looped links 49 and 50 having elongated slots 78 and 79 respectively therein. At the outer free end of the link 49 is pivoted as at 51 the arm 52 of a bell crank 53 pivotally mounted at 54. A 15 spring 55 constantly exerts a counter-clockwise torque on the bell crank 53. The other arm 63 of the bell crank has a head or pin portion 80 disposed in the annular groove 81 of a shifting head 82 formed integrally with or connected to 20 the type cylinder 1, axially movable upon a supporting shaft 83 but splined or otherwise connected therewith to rotate with the shaft 83. The shaft 83 is supported in adjustable rotational bearings 84 and 85.

25 As will now be apparent, when the upper ratchet piece 47, as viewed in Fig. 1, is stepped forwardly as above described, the pin 48 will advance in the slot 78 of the link 49 or tend to advance therein due to the exceedingly rapid 30 forward movement of the pin 48 and due also to the stepped or intermittent character of its movement. At the same time, the spring 55 will rock the bell crank 53 counter-clockwise and move the type cylinder 1 along the shaft 83, the 35 extent of the movement being determined by the extent of movement of the pin 48 which in turn is determined by the number of teeth or steps of advancement of the ratchet piece 47.

40 By means of the link and pin connections, 48—49, the intermittent movement of the ratchet piece 47 may go on freely unhampered by the inertia of the type cylinder and the parts connecting it with the ratchet teeth, and these latter parts may move with a steady or continuous movement, effected by an independent source of power, 45 namely the spring 55. At the end of movement of the ratchet piece 47, whereat the end of the slot 78 engages the pin 48, the type cylinder 1 is accurately brought to rest at a position corresponding to the movement of the ratchet piece 47, 50 which, in accordance with the selective number of impulses, positions the cylinder longitudinally with respect to a character thereon.

55 At the outer end of the link 50, a rack bar 55' is connected, and mounted to move longitudinally in unison with the link 50. A connecting rod 57 is pivotally connected to the rack bar 55 at 56 at one end and at the other end is pivoted as at 58 to a crank arm 59 pivotally supported at 60. A 60 spring 61 continually exerts resilient torque clockwise on the arm 59 and thus, acting through the connecting rod 57, exerts a longitudinal resilient thrust toward the left as viewed in Fig. 5, on the rack bar 55'. The rack bar 55' has rack teeth 67 on the under side thereof meshed with the teeth of a gear 68 secured to the shaft 83 in any suitable manner and rotatable therewith.

65 As will now appear, when the ratchet piece 47, the lower one as viewed in Fig. 1, is projected forwardly with the intermittent rapid movement 70 above described, the pin 48 thereof will advance in the slot 79. Concurrently therewith, the link 50 and rack bar 55' will be pulled forwardly with a steady or continuous movement by the spring 61,

thereby rotating the gear 88 and the shaft 83 and the type cylinder 1; and the extent of the rotational movement of the type cylinder 1 will be determined by the extent of movement of the ratchet piece 47 and pin 48, the movement being finally stopped, after the ratchet piece 47 stops moving, by engagement of the end of the slot 19 with the pin 48; and the rapid intermittent movement of the ratchet piece 47 will not be interfered with by the relatively great inertia of the other parts mentioned, associated therewith, but the rotary movement of the type cylinder 1 will be accurately determined and will rotate the type cylinder 1, one or more divisions thereof as described hereinbefore.

Since it is desired for each impulse in the magnets 7 and 8 to respectively rotate the type cylinder 1 by an amount equal to one division thereof and to move it longitudinally an amount equal to one division, the pitch diameter of the gear 88 must be proportioned so that it will turn the type cylinder 1 one division for each tooth or each step movement of the corresponding ratchet piece 47; and the ratio of the length of the bell crank arms 52 and 63 must be proportioned so that the longitudinal movement given to the type cylinder 1 will be correct for one complete division thereof for each tooth space or step of movement of the ratchet piece 47.

20 Where, as illustrated in Fig. 1, the longitudinal movement of the type cylinder 1 is in a direction at right angles to the longitudinal movement of the ratchet pieces 47, the bell crank arms 52 and 63 are preferably disposed at substantially 35 a right angle to each other and the pivot point 54 is preferably disposed so that the total movement of the bell crank arm will be substantially equal amounts on the opposite sides of corresponding center lines; for example, the bell crank arm 40 63 may move from one extreme position to the other, equal amounts on opposite sides of a horizontal line through the pivot 54, and the bell crank arm 53 correspondingly will move substantially equal amounts on opposite sides of vertical center line through the said pivot.

43. tical center line through the center of the ratchet pieces 47 will effect equal steps on the type cylinder 1. At the same time, the bell crank arm 63 may be longer than the bell crank arm 52 whereby any desired magnification of movement of the type cylinder 1 may be effected in correspondence to any suitable distance between the steps of the ratchet pieces 47. Again, if it be desired to move the type cylinder 1 unequal amounts as, for example, where some of the characters may occupy more longitudinal length on the cylinder, correspondingly the teeth spaces on the ratchet pieces 47 may be variable. Furthermore, although the lever arm 52 moves around a supporting pivot 54 and therefore its angular movement for two steps adjacent the left-hand end of the ratchet piece 47 is greater than for successive teeth, nevertheless, by the arrangement of the lever arms above described, this is exactly compensated for in the movement of the type cylinder 1; and for equally spaced teeth on the ratchet piece 47, the steps taken by the type cylinder 1 will be equal.

Referring again to Fig. 4, which illustrates one of the ratchet pieces 47 to an enlarged scale, I have shown the preferred form of the teeth 65 and 66. The teeth 65 comprise each a pawl-engaging portion 65' disposed substantially at a right angle to the direction of movement of the ratchet piece 47 and a rearwardly inwardly in-

clined portion 65" disposed at an angle of approximately 45° with the portion 65'. The teeth 66 comprises each a pawl-engaging portion 66', rearwardly outwardly inclined at an angle of approximately 30° from the direction of movement 5 and a rearwardly inwardly inclined portion 66", at an angle of approximately 45°, the shape of the teeth 65 and 66 thus provided being clearly illustrated in Fig. 4. I find that teeth of these forms cooperate more effectively and positively 10 in conjunction with the pawls 45 and 46 respectively than other shapes, but as will be understood by those skilled in the art, the teeth 65 and 66 may be, in form, considerably varied from that 15 illustrated in Fig. 4 without detracting unduly from a positive accurate ratcheting function thereof.

The type cylinder 1 may be mounted on the shaft 83 to rotate and move axially thereon by various mechanical arrangements, but I prefer the construction illustrated in Figs. 1, 2 and 3. As illustrated in these figures, the type cylinder has longitudinal grooves between the longitudinally disposed series of character supporting portions. In one of these grooves is disposed a key 82' preferably in the form of a slender rod, an end of which is mounted slidably in a bore 81' in the head 82, and is secured at one end in a suitable recess in a flange 83' of the gear 88. The key 82' is thus rigidly connected to the gear 88, rotates with it and forms a key or feather for guiding the longitudinal movements of the type cylinder 1, and also serves as a means to rotate the type cylinder 1 to communicate thereto rotary or oscillatory movement of the gear 88.

By this construction, the key or feather 82' may be disposed at a relatively great radial distance from the shaft 83 to reduce to a negligible amount any tendency of the cylinder 1 to jam thereupon; and the type cylinder 1 may be relatively loosely mounted upon the shaft 83 and have a relatively loose engagement with the key 82' whereby the type cylinder may in every case move freely and with great rapidity to its selected position.

At 10 is an electro-magnet having an armature 89 pivotally supported at 90 and provided on its free end with an anti-friction wheel or roller 92 engaging an inclined portion 93 of a switch indicated generally at 94. The armature 89 is maintained in its counter-clockwise position against the tension of a spring 89' by the engagement therewith of one arm 91 of a bell crank 98 pivotally supported at 99. The other arm 100 of the bell crank carries, pivoted at its free end as at 104, an equalizing bar 105 bridging and engaging the pins 48.

The electric system and circuits by which the elements of the receiver herein described are operated, constitute no part of the present invention, that part of the invention being more fully described and illustrated in the above mentioned patent application, Serial No. 591,224. It will suffice here to say that upon energization of the magnets 7 and 8 by impulses, these impulses energize the magnet 10 and attract the armature 89, freeing it from the end of the bell crank arm 91. When, as above described, the pins 48-48, either or both of them, move forwardly, they will leave their engagement with the equalizing bar 105 and the bell crank 98 will be free to be rotated clockwise around its pivot 99, as, for example, by a tension spring 106, to a position such as that in broken lines at 90'. When impulses cease, the energization of the magnet 75

10 ceases (as described in said application) and the spring 88' will retract the armature 88. Movement of the armature 88 will be stopped on the end of the arm 91.

When the bell crank is rotated counter-clockwise upon the restoring of the ratchet piece 47 in a manner to be described, the end of the arm 91 will engage and slide over a cam surface 101, on the armature 88 moving it counter-clockwise, and will hold it in this position by engagement with armature 88 on the relatively elevated portion 102.

As more fully described in said patent application, clockwise movement of the armature 88 will close the switch 94 and counter-clockwise movement will open it. The switch 94 controls energization and operation of a printing magnet indicated generally at 13, see Figs. 1 and 5 disposed under the type wheel 1 and, in connection with an inking ribbon 184 and a paper strip 125, prints each selected character of the type wheel 1 upon the paper strip, the ribbon 184 and strip 125 being fed forwardly after each character is printed.

The operation of the printing magnet 13 also operates a switch shown generally at 27 which controls the energization of a restoring magnet 14, as described in said pending application.

The function of the restoring magnet 14 is to restore the parts mechanically and electrically to their original or normal condition after the printing of a character and in preparation for the printing of the next successive character. This will now be described.

It will be observed that at the time of energizing the magnet, 14, the type cylinder 1 is in some one of its selective positions and therefore, the ratchet pieces 47-47 are in one or another of their forwardly stepped positions.

A depending armature 138, Fig. 5, is pivotally mounted as at 139 to swing toward and from the magnet 14, a pole piece 140 being provided on the armature 138 upon which the flux of the magnet 14 may act. The lower end of the armature 138 is pivotally connected to the two legs 141-141 of a U-shaped link 142, a pin 143 extending through the legs of the link and through the armature 138. A slot 144 in the legs 141 permits longitudinal movement of the ends of the pin 143 therein and a spring 145 is placed between the lower end of the armature 138 and the closed end of the link 142, whereby movement of the armature 138 may be initiated in quick response to the energization of the magnet 14 and without waiting for the inertia of the associated parts to be overcome, and movement of the armature transmitted to the link by the armature 138 may be cushioned to avoid shock and, for purposes of absorbing inertia of parts connected to the link 142, to permit the full stroke of the armature 138 to precede the movement of the said moved parts.

The legs 141 of the link 142 are pivotally connected as at 146 to the lower end of a lever 147 pivotally supported intermediate its ends and adjacent the pivot 146 on a ball bearing support 72. The opposite end of the lever 147 more remote from the bearing 72 is, as shown in Figs. 5 and 10, provided with a transverse bar 148 normally disposed forwardly of the pins 67 which depend from the ratchet pieces 47. And the lever 147 is also provided with a laterally extending pin 149 between the bar 148 and the bearing 72.

Upon attraction of the armature 138 by the

magnet 14 in the clockwise direction as viewed in Fig. 5, movement is transmitted through the link 142 to the lever 147, rocking it clockwise around the bearing 72, causing the bar 148 to move to the right and engage the pins 67 in whatever forward position they may have been selectively disposed, and to move them back to their normal position, during which movement the pins 48 and the links 49 and 50 operate through the bell crank 53 and through the rack bar 55 to restore 10 the printing cylinder 1 to its normal position. The springs 55 and 61 continuously act tending to move the links 49 and 50 forwardly and thus, acting through the pins 48, exert forward thrust on the ratchet pieces 47-47, but upon the completion of the rearward movement of the ratchet pieces 47, by means of the lever 147 as described, the ratchet pawls 45-45 will retain the ratchet pieces 47 in their rearmost or normal position.

The rearward movement of the pins 48 acts 20 upon the equalizing bar 105 to rock the bell crank 98 counter-clockwise causing the end of the arm 91 thereof to move over the cam 101 against the tension of the spring 106, into a position to engage the portion 102 of the armature 88 in which 25 position it may be subsequently held by a shoulder 102' on the armature. Thus the switch 94 is opened and held opened.

As will presently be referred to again, the magnet 14 will be de-energized after the lever 147 has moved through its stroke to reset the ratchet pieces 47, and to retract the lever 147 to a position suitable for its next operation, a spring 147' is provided connected at one end to the lever 147 and at its opposite end to a suitable point on the 35 stationary frame of the apparatus, the spring functioning to exert a counter-clockwise torque on the lever 147. When the ratchet pieces 47 have been restored to their reset position and held there by the pawls as above described, the 40 springs 68 are under tension and by their own reaction upon the head 71 tend to rotate the lever 147 clockwise in opposition to the tendency of the spring 147'. When the ratchet pieces 47 are ratched ahead, the tension in the springs 45 68 is gradually released, enabling the spring 147' to over-power the springs 68 and retract the lever 147. By suitably proportioning the tension of the springs 68 and 147', so that they suitably counter-balance each other, the retractive effort 50 of the springs 147' will only be able to retract the bar 148 a relatively short distance from the pins 67, and as the pins advance with the ratchet pieces 47, the bar 148 will retreat ahead of them so that the bar 148 is at all times a relatively 55 constant and relatively small distance away from the pins. Therefore, at each energization of the magnet 14 and resetting movement of the bar 148, the bar 148 moves only a short distance to engage the pin 67 whether the ratchet pieces have 60 been moved ahead one notch or one tooth, or the complete range of teeth; and therefore, the bar 148 engages the pins with the minimum of impact. The lever 147 thus has a floating movement which maintains the bar 148 in readiness 65 to effect a resetting action in the minimum of time after energization of the magnet 14, as well as with the minimum of shock.

At the completion of the operation of the restoring magnet 14 as above described, its own energizing circuit may be broken by the switch 94 or by the system of circuit and contacts and connections shown and described in said pending application and thereupon all the parts of the apparatus which have not heretofore been reset 75

now move to their normal or reset positions and the entire apparatus is ready for another character printing cycle of movements.

It is to be observed that by sending impulses to both magnets 7 and 8 simultaneously, the type cylinder will rotate and move longitudinally, both movements occurring concurrently and thus the type cylinder is moved to its selective position with a screwing movement on all or a part of its 10 selection movement.

By reference to Figs. 5, 7, 8, and 10, which illustrate an actual apparatus in which my invention may be embodied, and which apparatus has been developed into somewhat diagrammatic form in 15 Fig. 1, it will be seen that the apparatus may conveniently be assembled upon a frame comprising a base portion 300, a floor portion 301 spaced vertically thereabove and a vertical wall portion 303 standing on or arising from an intermediate 20 portion of the floor 301.

As shown in Fig. 7 and partly in Fig. 5, the mechanism for selectively moving the type cylinder 1 may conveniently be mounted upon the floor portion 301; and as shown in Fig. 5, the 25 magnets 13, 14 and 7 and 8 may conveniently be disposed between the floor portion 301 and the base 300, the magnet 13 and its frame being conveniently suspended from the under side of the floor portion 301, as may also the magnet 14 30 and its frame, and magnets 7 and 8, see also Fig. 7, may conveniently be disposed on the upper side of the base 300.

The magnet 10 as indicated in Fig. 7 may be disposed at right angle to the floor portion 301 35 and may be disposed generally thereunder. To avoid complications of the drawings, this magnet has been illustrated in a horizontal position in Fig. 1, but it is believed that the construction thereof and of the correlated parts will be clear 40 from Fig. 7 without further illustration or description.

In Fig. 5 a single magnet 14 is illustrated. In some instances I may employ two magnets, in 45 which case the second magnet would be disposed directly behind the magnet 14 illustrated in Fig. 5. In such case also it would be preferred to provide two magnetic circuits one for each magnet. As described hereinbefore the magnet 50 circuit of the electro-magnet 14 comprises a horizontal element 311 by which it may be supported on the floor portion 301, a depending leg 312 and magnet core and magnet armature 140; and these parts are preferably duplicated except 55 as to the armature 140 when two windings are employed.

Such a two magnet construction is shown in Fig. 9 which may be considered as viewed from the plane 9 of Fig. 5, with the parts broken away at the pivotal bearing 139. The two magnet 60 windings 14a-14a have a common yoke 320 and the armature 140 may be attracted by both magnet windings 14a-14a. The armature 140 has a central head portion 321 thereon transversely through which extends a short pin 322, the ends 65 of the pin mounting the inner race elements 323-323 of ball bearings, the outer race elements of which 324-324 are supported in suitable bores in arms 325-325 of the common yoke 320.

The pin 322 corresponds to the pivot bearing element 139 in Fig. 5. By this construction 70 the armature 140 may pivot around the ball bearings described and furthermore, which is an important feature of this construction, the magnetism from the magnets 14a-14a flows not 75

only through the armature 140 and yoke 320 but on its way from one to the other flows into the head 321 and sends through the inner and outer bearing elements 323 and 324 and through the 5 balls such as 326 therebetween.

The magnetism by attracting the balls and their race elements into tight engagement with each other, eliminate every trace of lost motion in these bearings, and at the same time, due to the ball type of bearing, does not introduce 10 friction thereby; and furthermore, by this construction, a continuous magnetic path of low reluctance is provided, the only air gap being that between the cores of the magnets 14a-14a and the armature 140. Thus, a very efficient as well 15 as silent and lost motion proof magnetic circuit and armature mounting is provided having properties particularly suitable and advantageous in mechanisms of the kind under consideration.

The actual construction of the armature 35 of 20 the magnets 1 and 8 is to be particularly noted. In the preferred construction, the armature comprises a portion 315 disposed opposite the core of the magnet, which portion is pivotally supported at 37, and a relatively slender rod portion 25 35 rising vertically therefrom, the upper end of which as plainly shown in Figs. 5 and 7 engages the arm 39 of the bell crank-form ratchet pawl supporting pieces. By supporting the magnet 1 30 on the base 300 and the ratcheting mechanism 30 referred to upon the spaced floor 301, a considerable length of rod portion 35 may be provided which makes it possible to so proportion the length and diameter of the rod portions 35 35 that they may bend under the force applied thereto by the windings 7 and 8. Thus for a considerable movement of the upper ends of these rod portions 35 it is only necessary to move the armature portion 315 a very slight distance and the armature portion 315 may respond immediately 40 to the impulses, followed by movement of the rod portion, the rod portion functioning as a resilient rectilinear bar spring. It will be observed that this movement of the rod portion 35 is distinctly different from that of an armature 45 portion which merely moves under the influence of magnetism and is retracted by a spring, and in which the inertia of the parts must be continuously overcome, during their vibration, by the 50 direct pull of the magnet.

The rod-like portions 35 have a natural frequency or period of vibration which may be made to correspond to the rate at which the impulses occur, and thus the effect of the magnetic impulses from the magnets 7 and 8 may be described as that of keeping the rod-like armatures in vibration rather than of bodily moving them. 55

The armatures 35 may be retracted in any suitable manner but I prefer to retract them by springs 316-316, Fig. 7, acting through the bell 60 crank arms 39-39.

Having thus described my invention, I am aware that numerous and extensive departures may be made from the embodiment herein illustrated and described, but without departing 65 from the spirit of my invention.

I claim:

1. In a step-movement escapement selective mechanism for electrically actuated typewriters or the like, a ratchet piece comprising a body 70 portion having parallel rows of teeth on opposite sides thereof, a double pawl having a tooth normally in engagement with the teeth of the first row and a pawl normally laterally spaced from the teeth of the second row, means for constrain- 75

- ing the ratchet piece to move forward longitudinally, means for transversely reciprocating the pawl teeth, the teeth of the first row provided with a surface at right angles to the direction of movement and a surface at an angle of approximately 45° to the direction of movement, and the teeth of the second row provided with two faces at angles of approximately 45° to the direction of movement.
10. 2. In a step movement escapement selective mechanism for electrically actuated typewriters or the like, a ratchet piece comprising a body portion having a predetermined direction of movement, and provided with two rows of teeth, a double pawl having a tooth engageable with the teeth of one row and a pawl engageable with the teeth of the other row, means for reciprocating the pawl teeth, the teeth of the first row provided with a surface at right angles to the direction of movement portion and a surface at an angle of approximately 45° to the direction of movement, and the teeth of the second row provided with two faces at angles of approximately 45° to the direction of movement.
15. 3. In a step movement escapement selective mechanism for electrically actuated typewriters or the like, a ratchet piece comprising a body portion having two rows of teeth thereon, means for constraining the body portion to move forwardly in generally the direction of the teeth rows, a double pawl having two teeth alternately movable into the path of the rows of teeth upon reciprocation thereof, means for reciprocating the pawl teeth, the teeth of one row having each a surface extending from the body portion at an angle sufficiently near 90° with the path of movement of the teeth that when engaging one pawl tooth in its path, it will stop movement of the body portion, and the teeth of the other row having each a surface extending from the body portion at an angle sufficiently less than 90° with the path of movement that upon engaging the other pawl tooth in its path the tooth will tend to move said pawl tooth out of said engagement and out of the path of movement of the ratchet teeth.
4. In a step movement escapement selective mechanism for electrically actuated typewriters or the like, a ratchet piece comprising a body portion having two rows of teeth thereon, means for constraining the body portion to move forward in generally the direction of the teeth rows, a double pawl having two teeth alternately movable into the path of the rows of teeth upon reciprocation thereof, means for reciprocating the pawl teeth, means for constraining the body portion to move forward in generally the direction of the teeth rows, the teeth of one row having each a surface extending from the body portion at an angle to the path of tooth movement sufficiently near 90° that when engaging one pawl tooth in its path, it will stop movement of the body portion, and the teeth of the other row having each a surface extending from the body portion at an angle sufficiently less than 90° to the path of movement that upon engaging the other pawl tooth the said teeth of the row will tend to move said pawl tooth out of said engagement and out of the path of movement, and the teeth of both said rows having other surfaces extending from the body portion at an angle sufficiently less than 90° that upon movement of the body portion in the reverse direction, the said teeth of the body portion tend to move an engaged pawl tooth out of engagement and out of the path of movement.
5. In a step movement mechanism an element having a row of ratchet teeth, resilient means constraining it to move in the direction of the tooth row, a pawl and means to oscillate it to engage and disengage successive teeth of the row to permit a step by step movement of the element in said direction, means for restoring the element by movement in reverse direction comprising an abutment on the element, an oscillatory arm connected to the resilient means and engageable with the abutment in one direction of oscillation to move the elements and in the other direction of oscillation disengaging the abutment and tensioning the said resilient means and means to oscillate the arm.
6. In a step movement mechanism an element having a pair of parallel rows of ratchet teeth, resilient means constraining the element to move in the direction of the tooth rows, a pawl and means to oscillate it to engage and disengage the successive teeth of the two rows alternately, to permit a step by step movement of the element in said direction, means for restoring the element by movement in the reverse direction comprising an abutment on the element, an oscillatory arm connected to the resilient means and engageable with the abutment in one direction of oscillation, and in the other direction of oscillation disengaging the abutment and tensioning the said resilient means and means to oscillate the arm.
7. In a step movement mechanism an element having a row of ratchet teeth, means constraining it to move in the direction of the tooth row, a pawl and means to oscillate it to engage and disengage successive teeth to permit a step by step movement of the element in said direction, a mechanism controlled by movement of the element comprising a member having a telescopic connection with the step mechanism element and independently constrained to move relative thereto.
8. In a step movement mechanism an element having a pair of parallel rows of ratchet teeth, means constraining the element to move in the direction of the tooth rows, a pawl and means to oscillate it to engage and disengage the successive teeth of the two rows alternately to permit a step by step movement of the element in said direction, a mechanism controlled by movement of the element comprising a member having a telescopic connection with the said element and independently constrained to move relative thereto.
9. In a step movement mechanism a pair of elements having each a row of ratchet teeth, means constantly and independently constraining the elements to move in the direction of the tooth rows, a pawl associated with each element and means to oscillate it to engage and disengage the successive teeth of the element to permit a step by step movement of the element in said direction, an abutment on each element, a bridging element, means yieldably maintaining the bridging element in bridging engagement with both abutments, and a mechanism connected to the bridging element operable by movement thereof communicated thereto by movement of either or both step movement elements.
10. In a step mechanism a pair of elements each having a pair of parallel rows of ratchet teeth, means constraining each element independently of the other to move in the direction of the tooth rows, a pawl associated with each element

and means to oscillate it to engage and disengage the successive teeth of the two rows alternately of the associated element to permit a step by step movement of each element in the said direction independently of the step movement of the other element, an abutment on each element, a bridging element, means yieldably maintaining the bridging element in bridging engagement with said abutments, and a mechanism connected to the bridging element operable by movement thereof, communicated thereto by movement of either or both of said step movement elements.

11. In a step movement mechanism for typewriters and the like, a pair of elements having each a row of ratchet teeth, means constantly and independently constraining the elements to move in the direction of the tooth rows, a pawl associated with each element and means to oscillate it to engage and disengage the successive teeth of the element to permit a step by step movement of the element in said direction, a multi-character cylinder movable selectively to printing positions by rotary and axial movements thereof, separate means for moving the cylinder axially and rotatively, and means connecting said toothed elements respectively to said cylinder moving means.

12. In a step movement mechanism, an element having a row of ratchet teeth, means constraining the element to move in the direction of the

tooth row, an oscillatory bell-crank-form pawl, means to oscillate it by one arm thereof, the pawl having a portion of the other arm engageable and disengageable with successive teeth upon oscillation thereof and normally constrained in the direction to engage the teeth, and upon oscillation permitting a step by step movement of the element in the direction of the tooth row and the means to oscillate the bell-crank being a resilient reed-like extension of an electro-magnetic vibratory armature overlapping the said bell-crank arm at an angle thereto.

13. In a step movement mechanism, an element having a pair of parallel rows of ratchet teeth, means constraining the element to move in the direction of the tooth rows, an oscillatory bell-crank-form pawl, means to oscillate it by one arm, the pawl having a portion on the other arm engageable and disengageable with successive teeth of the two rows alternately upon oscillation thereof and normally constrained in the direction to engage the teeth of one row, and upon oscillation permitting a step by step movement of the element in the direction of the tooth rows, the means to oscillate the bell-crank being a resilient reed-like extension of an electro-magnetic vibratory armature overlapping the said bell-crank arm at an angle thereto.

WILLIAM C. ROE.
